James Frank Thomas*

UNITED STATES PATENT OFFICE.

FRANK THOMAS, OF SCRANTON, PENNSYLVANIA, ASSIGNOR OF ONE-HALF
TO DAVID B. HAND, OF SAME PLACE.

PAD FOR HORSES' FEET.

SPECIFICATION forming part of Letters Patent No. 576,522, dated February 2, 1897.

Application filed July 10, 1896. Serial No. 598,769. (No model.)

To all whom it may concern:

Be it known that I, FRANK THOMAS, a citizen of the United States, residing at Scranton, in the county of Lackawanna and State of Pennsylvania, have invented certain new and useful Improvements in Soaking and Driving Pads for Horses' Feet; and I do hereby declare the following to be a full, clear, and exact description of the invention, such as will enable others skilled in the art to which it appertains to make and use the same.

My invention relates to soaking and driving pads for horses' feet; and it consists of certain novel constructions, combinations, and arrangement of parts, as will be hereinafter described and claimed.

In the accompanying drawings, Figure 1 is a bottom view of a horse's foot provided with a horseshoe and with my invention applied thereto. Fig. 2 is a longitudinal section of the same, and Fig. 3 is a perspective view of my improved pad disconnected from a horse's foot.

My improved pad is designed either for soaking or driving purposes, and to adapt it for both of these purposes it is necessary that the pad should be so constructed as to hold moisture a considerable length of time and also be securely held to the shoe at a number of points and yet be capable of ready attachment and removal. Pads have been constructed which have been capable of being secured to a horse's foot, but all of them have not been so constructed that they could be used as a soaking-pad and at the same time were strongly enough secured to the foot as to stand the hard usage of driving without becoming detached from the foot.

My improved pad consists of a body portion A, constructed of any suitable absorbent material, preferably felt, and cut into a suitable shape to adapt it to be tightly fitted into the space inclosed by the horseshoe.

B represents a spring, which is made from a single piece of metal and bent into the shape shown, so as to form lateral looped projections b b and a long loop b'. This spring is secured permanently to the bottom or ground-surface of the pad and held in proper position by means of a large-headed rivet b², as shown.

C represents an independent U-shaped spring, which is bent into the form of a rec-

tangular loop, having its forward ends bent laterally, as at c c, for a purpose to be presently described. This spring is secured to the ground side of the pad by means of rivets 55 near the heel end, or in any other suitable manner, and extends forward approximately the entire length of the pad.

D represents a fastening toe-plate, which is provided with a longitudinal slot d. The rivet 60 b² passes through the slot d, and thus holds the plate in position and at the same time permits the plate to move longitudinally back and forth, as will be presently described. The office of this adjustable toe-plate is important, 65 for if the pad when applied to the horse's foot does not completely fill the space inclosed by the shoe, and the pad does not fully reach the toe end of the shoe, the toe-piece can be readily slid forward between the hoof and the under 70 side of the shoe.

By the employment of two independent springs B and C, in the event of one spring getting out of order, or for any reason it is desired to remove one spring, it can be done 75 or another spring inserted without disturbing the other spring. But a more important result is secured in that the pad can be fastened onto the foot at five different points around the shoe, thereby more securely holding the pad in position around the shoe and rendering it less liable to become detached therefrom, and also holding the pad more snugly against the frog of the foot and keeping the parts cooled when the pad is being 85 used for soaking purposes, and preventing gravel and dirt getting into the hoof when the pad is used while driving. It is essential that the pad be well pressed up against the frog and that it be well secured all around its edges 90 to the shoe.

The pad is applied to the foot as follows: When it is to be used for soaking purposes, to reduce fever or relieve pain in the foot or leg, it is first thoroughly soaked with water 95 or some medicated preparation. Then the pad is placed in the space inclosed by the shoe and the toe-plate, if desired, slid between the hoof and the shoe at the toe. Then the spring C is compressed by having its ends 100 brought toward each other, and the laterally-extending ends are then allowed to slip under

the shoe. Next the looped spring B is similarly compressed until it falls within the space inclosed by the shoe, when it is released and allowed to spring under the shoe.

5 From the foregoing specification it will be seen that the device is simple in construction and not liable to get out of order and can be applied to and detached from a shoe without any difficulty.

10 Having now described my invention, what I claim as new, and desire to secure by Letters Patent, is—

15 1. A soaking or driving pad for horses' feet, comprising in its construction a main body portion constructed of a suitable absorbent material cut into such shape and size as to fit snugly into the space inclosed by the horseshoe, a looped spring attached to the ground-surface of the pad and provided with lateral 20 projections, and a longitudinally-adjustable toe-piece also secured to said pad for holding the pad in position against the foot, substantially as described.

25 2. A soaking or driving pad for a horse's foot, comprising in its construction a main body portion constructed of a suitable absorbent material cut into such shape and size as to fit snugly in the space inclosed by the horseshoe, a looped spring attached to the ground-

30 surface of the pad and provided with lateral projections, and an approximately **U**-shaped spring extending approximately the entire length of the pad and provided with lateral projections at its forward ends, substantially as described.

35 3. A soaking and driving pad for a horse's foot, comprising in its construction a main body portion constructed of a suitable absorbent material cut into shape and size to fit snugly in the space inclosed by the horseshoe, 40 a looped spring attached to the pad and provided with lateral projections, an approximately **U**-shaped spring extending approximately the entire length of the pad and provided with lateral projections at its forward 45 ends, and a longitudinally-adjustable toe-plate provided with a longitudinal slot, and a rivet passed through the slot in the plate for securing it in position and guiding its movement, substantially as described.

50 In testimony whereof I hereunto affix my signature in presence of two witnesses.

his
FRANK X THOMAS.
